UNITED STATES PATENT OFFICE.

WILLIAM C. FREEMAN, OF LOUISIANA, MISSOURI.

DESIGN FOR A DIPPER.

SPECIFICATION forming part of Design No. 15,051, dated June 10, 1884.

Application filed June 9, 1883. Term of patent 11 years.

To all whom it may concern:

Be it known that I, W. C. FREEMAN, of Louisiana, Pike county, Missouri, have invented a Design for Dippers, of which the following is a specification.

Figure 1 of the drawings is a side view. Fig. 2 shows a perspective view of my newly designed dipper.

The invention consists in a peculiar configuration of the bowl of the dipper and handle thereof, the whole forming a new design, which gives to the dipper a neat and ornamental appearance, substantially as hereinafter described, and shown in the drawings.

15 A is the bowl, which is of hemispherical configuration, the same presenting a convex exterior, b, and a concave interior, c, excepting around its upper edge portion, where the interior is of a graceful convex form, giving a varnishing or sharp finish to the upper edge of the bowl, that adds greatly to the symmetry of the whole bowl, as more clearly shown in Fig. 2.

20 B is the handle, the inner end portion, f, of which, where it joins the bowl, is swelled out or enlarged, and of convex form both in direction of its length and width, converging to a point at its lower end, and presenting as a whole a bulge or protuberance of partial egg

shape, as shown, and joining at its upper end 30 by short concave lines the main body or portion of the handle, which is of circular form transversely, and of reverse tapering configuration in direction of its length, the one and inner taper being longer than the outer taper, 35 and the two tapers forming more or less a prostate spheroidal figure near the outer end of the handle. The enlarged inner end portion, f, of the handle, shaped as shown and described, gives a bulbous or root-like appearance to the handle where it juts or projects from the bowl.

What I claim as new and of my invention is—

The within-described design for a dipper, which consists of a bowl, A, of hemispherical 45 shape, with its interior c of concavo-convex configuration, terminating in a sharp outline on the upper edge of the bowl, and a handle, B, of circular form in the transverse section, and reversely-tapering shape longitudinally, 50 terminating at its inner end in a partial bulb-like protuberance, f, of convex form both in direction of its length and width, and converging to a point at its lower end, as shown.

WILLIAM C. FREEMAN.
